UNITED STATES PATENT OFFICE.

ROY S. INNES, OF MADISON, SOUTH DAKOTA.

AUTOMOBILE RADIATOR-THAWING DEVICE.

Application filed April 26, 1923, Serial No. 634,694. Renewed March 14, 1925.

To all whom it may concern:

Be it known that I, ROY S. INNES, a citizen of the United States, residing at Madison, in the county of Lake and State of 5 South Dakota, have invented certain new and useful Improvements in Automobile Radiator-Thawing Devices, of which the following is a specification.

This invention relates to certain new and 10 useful improvements in radiator thawing devices and the primary object thereof is to provide means for automatically effecting thawing of the ribbon tubes upon freezing thereof.

15 The invention briefly proposes the use of an overflow pipe which is modified so as to receive the steam that is generated in the radiator upon running of the engine and to distribute same at various points throughout the radiator to thereby effect heating of the frozen water and consequent thawing thereof.

20 The invention has for its further object simple and inexpensive modification of the 25 overflow pipe and still further aims to provide means of the character set forth which can be easily and quickly attached to the radiators of automobiles now in use or which can be built into the radiators during manufacture of the latter.

In the drawings:—

Figure 1, is a rear perspective view of an 35 automobile radiator, showing the present invention applied thereto as an attachment;

Figure 2, is a detail view partly in section showing the present invention built into a 40 radiator at the time of manufacture thereof;

Figure 3, is a transverse sectional view of a radiator having the invention built 45 therein;

Figure 4, is a detail perspective view of the overflow pipe, partly broken away and in section;

Figure 5, is a detail view of the attaching 50 strip, and

Figure 6, is a transverse sectional view showing the manner of securing the attaching strip to the parts.

In proceeding in accordance with the 55 present invention, the overflow pipe 1, has its upper end 2 completely closed, while its lower end is open to permit the escape of the overflow or surplus water. A relatively large steam and water inlet 4 is provided at the upper end of the pipe just below the closed upper end 2 thereof. The remainder

of the pipe is formed throughout with a series of steam discharge openings or distributing outlets 3, which latter may be of any shape and which may also vary as to 60 location and number. The openings 3 extend throughout the length of the pipe 1 and face the usual water cells of the radiator R.

The pipe, as depicted in Figure 1 of the 65 drawings, is secured in position with its inlet 4 in the filling neck N of the radiator, an attaching strip 5 being employed to rigidly connect the pipe 1 to the rear side of the radiator R. The strip 5 is of approximately 70 U-shape in cross-section receiving and soldered at 7 to the pipe 1, and has wings 6 which are also soldered to the radiator, in the instance of the invention being applied to radiators now in use, or 75 otherwise stated radiators that are not especially built for use with the present invention.

In cases where the invention is to be built 80 into the radiator, or incorporated therein, during manufacture, the rear sides of the cells or as generally termed the honey-comb, are cutaway to afford a vertical channel or chamber 8 of suitable size to receive the pipe 1. The pipe 1 is preferably soldered 85 in place at 8 and is covered by a flat metal strip or plate 9 which latter is soldered to the rear side of the honey-comb and to the pipe to assist in securing the latter in place.

In operation, as the steam rises in the 90 frozen radiator, same enters the inlet 4 and escapes through the outlets 3 and is caused to impinge against the radiator cells, melting the ice and setting up circulation of the 95 water, the heat being gradually transmitted by the circulation thus set up to the adjacent cells, until the entire radiator becomes thawed out. By having the upper end of the pipe closed, the steam cannot escape upwardly therefrom after having entered the 100 pipe. The inlet 4 also serves to receive any overflow of water in filling of the radiator.

What is claimed is:—

1. In combination with an automobile radiator, an overflow pipe disposed vertically 105 and centrally of the width of the radiator and having a closed upper end and an inlet arranged in the filling neck of the radiator, said pipe extending to a point adjacent the lower end of the radiator and formed with 110 a series of outlets, the said outlets being so disposed as to cause steam entering the pipe

at the inlet thereof to egress through the outlets and be impinged against the adjacent cells of the radiator on opposite sides of the pipe to effect thawing of the latter and means to connect the pipe to the radiator.

2. In combination with an automobile radiator having a central vertical channel formed in its rear side, an overflow pipe engaged in said channel and having an inlet 10 arranged in the filling neck of the radiator, said pipe extending to a point adjacent the lower end of the radiator and formed with a series of outlets, the said outlets being so disposed as to cause steam entering the pipe 15 at the inlet thereof to egress through the outlets and be impinged against the adjacent cells of the radiator on opposite sides of the pipe to effect thawing of the latter and means to attach the pipe in position including a metal member extending transversely across the channel and pipe and engaged over the outer side of the overflow pipe and connected to the radiator.

3. In an automobile radiator thawing device, a pipe having an inlet at its top and

formed to extend within the filling neck of the radiator, said pipe formed with a series of steam outlets arranged to cause the steam from the pipe to be directly impinged against the radiator, and to be diffused on opposite 30 sides of the pipe, and means to affix said pipe to the rear side portion of the radiator and at substantially the center of the width of the radiator.

4. In combination with an automobile 35 radiator having a central vertical channel formed in the rear side of its cells, an overflow pipe engaged in said channel and having an inlet arranged to extend in the filling neck of the radiator, said pipe extending to 40 a point adjacent the lower end of the radiator and being formed with a series of outlets, the said outlets being so disposed as to cause steam entering the pipe at the inlet thereof to egress through the outlets and be 45 impinged against the adjacent cells of the radiator to effect thawing of the latter, and means to connect the pipe to the radiator.

In testimony whereof I affix my signature.

ROY S. INNES.
